[57] **ABSTRACT**

A perpetual calendar and writing instrument holder is attachable to any convenient surface, such as a telephone instrument body, and has an hollow housing with an opening in its outer peripheral surface. A protuberance extends outwardly from the peripheral surface and contains a passageway therethrough generally tangential to the housing, about 90° from the closest edge of the opening. A rotatable inset is positioned within the housing having a plurality of months disposed about its outer periphery, a selectable one of the months to be fully visible through the opening.

Howard C. Meakin

**PERPETUAL CALENDAR AND WRITING
INSTRUMENT HOLDER**

BACKGROUND OF THE INVENTION

The present invention relates generally to improvements in writing instrument holders and perpetual calendar instruments attachable to surfaces and, more particularly, it relates to an improved attachable perpetual calendar and writing instrument holder.

Heretofore perpetual calendars were mechanical, bulky devices, which required various manipulations of the user to select and position the date in a visible position. Because of their elaborateness and degree of complexity, these calendars required relatively large bases, so that they were normally positioned on a pedestal or desk support. Oftentimes these perpetual calendars had pen holders associated on the same base. These prior art perpetual calendar devices possessed numerous drawbacks and disadvantages. Among these drawbacks were their expense, difficulty to manipulate and fabricate, occupying a relatively large amount of space on a desk, and the complexity, relatively high cost and limited application.

SUMMARY OF THE INVENTION

It is a principal object of the present invention to provide an improved perpetual calendar and writing instrument holder.

Another object of the present invention is to provide an improved mechanism allowing the current month to be easily visible and easily changed.

It is still another object of the present invention to provide an improved perpetual calendar and writing instrument holder, which can be mounted on any convenient surface and which occupies only a relatively small space.

It is still another object of the present invention to provide a perpetual calendar and writing instrument holder of the above nature, characterized by its simplicity, reliability, ease of applying to any convenient surface, low cost, ruggedness, versatility, and adaptability.

In a sense the present invention contemplates the provision of a perpetual calendar and writing instrument holder including an outer housing having a base and a cylinder wall extending transversely thereto defining a volume, said cylindrical wall having an opening therein communicating with said volume. A protuberance extends outwardly from the cylindrical wall, and has a passageway therethrough, generally tangential to the cylindrical wall. A cylindrical member is rotatably positioned within said volume and has an outer cylindrical surface juxtaposed to the inner peripheral surface of said cylindrical wall. Indicia means disposed about the outer surface of the cylindrical member and selectively adaptable to appear through said opening in said cylindrical wall in said housing. Means are adapted to rotate about the cylindrical member, and other means retain the member within the housing. The indicia means is advantageously seven months, each of which begins on a different day of the week. Another feature of the improved perpetual calendar and writing instrument holder is the structure of the rotatable means which includes holding means for retaining the rotatable member within the housing. Also the passageway through the protuberance through which the writing instrument is positioned is about 90° and the closest

edge of the opening which allows the opening to be readily viewed by the user, while holding the writing instrument in a position so it will not drop or fall from the opening.

The improved calendar and writing instrument holder is reliable, inexpensive, rugged, easy to apply to any convenient surface and operate, and of great versatility and adaptability.

BRIEF DESCRIPTION OF THE DRAWING

FIG. 1 is a perspective view of the calendar and writing instrument holder embodying the present invention showing a writing instrument in phantom;

FIG. 2 is a cross sectional view taken along Line 2—2 of FIG. 1; and

FIG. 3 is a layout of one form of the calendar disposed about the outer peripheral surface of the rotatable member.

DESCRIPTION OF THE EMBODIMENT

Referring now to the drawing, which illustrates a preferred embodiment of the present invention, reference numeral 10 generally designates a perpetual calendar and writing instrument holder which is advantageously

formed of a synthetic organic polymeric resin such as polyethylene, polypropylene, nylon, polyvinyl chloride, or the like, in any suitable manner. The calendar and writing instrument holder, in turn, includes an outer housing 12 having a rear base 14 and a cylindrical wall 16 extending transversely to base 14 and defining a volume 18. Cylindrical wall 16 has an opening 20 therein which communicates with volume 18. Extending radially outwardly from wall 16 is a protuberance or extension 22 having a passageway 24 therethrough. Passageway 24 is generally cylindrical for receiving a writing instrument, such as a pencil or ball point pen, indicated in phantom as 26 in FIG. 1. Passageway 24 is advantageously tangential to cylindrical wall 16 and, as shown, is about 90° removed from the closest edge 28 of opening 20.

Slideably and rotatably disposed within volume 18 is an inner member 30 having a base or front surface 32 and having a cylindrical, peripheral wall 34 extending generally transverse to front surface 32. Cylindrical wall 34 has an outer diameter dimensioned to be slightly less than the inner diameter of outer cylindrical wall 16, such as seen best in FIG. 2. Centrally disposed on front plate 32 and coaxial thereto is a knob 36 roughened on its outer peripheral surface 38, so as to aid in rotating member 30.

Extending generally radially inwardly from the outer edge of peripheral wall 16 are a pair of diametrically opposed fingers 40, which extend below the inner diameter of peripheral surface 16, as seen best in FIG. 2. The edges of fingers 40 are tapered inwardly, so as to form beveled edges forming retaining surfaces, indicated at 42. Fingers or retaining elements 40 hold inner member 30 in operative position within outer member 12, as seen best in FIG. 2. The outer diameter of peripheral wall 34 of inner member 30 is dimensioned to allow free rotation relative to wall 16. Disposed about the outer surface of peripheral wall 34 is indicia, which, as shown, takes the form of a series of months, seven of which are shown. These months are dimensioned to be fully disposed through opening 20. As illustrated, this indicia is mounted on a strip 44 which is of relatively small thickness, as seen best in FIG. 2. Also, if de-

sired, indicia could be molded on the outer surface of wall 34.

As shown, the months on strip 44 are in sequence, with each month beginning on an alternate day of the week where, as shown in FIG. 3, the first month on the strip, indicated as 46A, begins on a Sunday, month 46B begins on a Monday, month 46C begins on a Tuesday, etc. The 31st day is indicated in a different color or typograph than the other dates, since the 31st may or may not be applicable with the actual month of the year.

To assemble, the strip containing the months or other indicia is positioned about the outer peripheral surface of wall 34 of inner member 30, and the unit is forced through between stop members 40 to spring these members apart and then allow them to return to their unstressed position, when inner member 30 is fully disposed within volume 18. The return of arms 40 locks in position and yet allows it to be freely rotatable within volume 18.

Inner member 30 is rotated by the user rotating a knob 36 to position the selected month within opening 20. In other words, if the actual month begins on a Tuesday, then month 46C is positioned within opening 20. The unit is assembled with an adhesive applied to the rear panel 14 of unit 10. The adhesive can be protected by a suitable covering which can be peeled off when ready for use. The unit can be mounted on any convenient surface such as a telephone, wall, or the like and the writing instrument 26 is readily available as well as having the date readily available.

While the months are shown disposed about the peripheral surface of inner member 30, if desired, space can be provided for important telephone numbers such as police, fire and the like, which numbers can be writing in the space and can be quickly selected when needed by rotating knob 36. In this form, rather than the date and the month, a plain piece of paper with lines can be mounted about the outer surface of the periphery of inner member 30. Therefore, in the present invention, even though "perpetual calendar" is used, the outer surface of inner member 30 can be used for placing desired or important telephone numbers; hence, when used in the claims, the "calendar" would also encompass this construction.

Also, while one form of holding member 40 is shown, other forms may be used such as lugs, split cylinder wall construction, and rib, fingers, or the like.

While there has been described a preferred embodiment of the present invention, it is apparent that many

other alterations, omissions and additions may be made without departing from the spirit thereof.

What I claim is:

1. A perpetual calendar and writing instrument holder for attachment to telephones and the like comprising an outer cylindrical housing including a base defining an end wall having means for attachment to a telephone and a cylindrical peripheral wall extending transversely thereto defining a cylindrical cavity, said cylindrical wall having an opening there defining a window communicating with said cavity means for holding a writing instrument including a protuberance formed with and extending outwardly from said cylindrical wall, said protuberance having a passageway therein generally tangential to said cylindrical wall for slidably engaging a writing instrument, an inner cylindrical drum rotatably positioned within said cavity and having a peripheral face juxtaposed to the surface of the cylindrical wall of said outer housing, indicia means disposed about the drum peripheral face and adapted to selectively appear through the opening in the cylindrical wall of said housing, means adapted to rotate said drum, and means retaining said drum within said housing.

2. The device of claim 1 wherein said retaining means includes at least one resilient stop member extending radially inwardly from said outer cylindrical wall of said housing and being outwardly flexible in response to axial pressure attendant to assembly of said drum and returnable to its unflexed position when said drum is fully assembled.

3. The device of claim 1 wherein said passageway is about 90° from the closest edge of said opening in the cylindrical wall of the housing.

4. The device of claim 1 wherein said drum further includes a front face integrally connected to the drum peripheral face.

5. The device of claim 4 wherein said rotating means is a knob positioned coaxially on the front face of said drum.

6. The device of claim 1 wherein said indicia means is a series of months consecutively positioned so that the month begins alternately on different days of the week.

7. The device of claim 1 wherein said retaining means is a resiliently positioned flange extending radially inwardly from the cylindrical wall of said outer members.

8. The device of claim 1 wherein said outer housing and drum are formed of synthetic polymeric resin.
